PHONOGRAPH RECORD RACK

Donald D. Pauldine, Elmira, N. Y.

Application October 3, 1950, Serial No. 188,177

1 Claim. (Cl. 312—10)

2

The present invention relates to improvements in phonograph record racks and more particularly to the type of rack which is well adapted to form an attractive piece of furniture and which may be combined with radio, phonograph and television combinations.

A primary object of the present invention is to provide an improved phonograph record rack wherein means are provided for varying the size of the means for receiving the records whereby records of the different diameters may be mounted therein.

A further object of the present invention resides in the novel arrangement whereby the adjustment means of the present invention may be secured to the shelves of the rack for changing the size of the slots receiving the records.

Still another object of the present invention resides in the provision of means whereby the attachment for varying the diameter of the slots may be predetermined for receiving records of the long playing size.

Further objects of the present invention are to provide such means that are simple in construction, economical of manufacture and well adapted to varying designs for use in combination with radios, phonographs, television sets and combinations thereof.

Various other objects and advantages will become apparent from the detailed description to follow.

The best form in which I have contemplated applying my invention is clearly illustrated in the accompanying drawings, wherein:

Figure 1 is a front elevational view of the phonograph record rack of the present invention;

Figure 2 is a vertical transverse sectional view taken substantially along the plane of line 2—2 of Figure 1;

Figure 3 is a detail sectional view taken substantially along the plane of line 3—3 of Figure 1; and

Figure 4 is a detail sectional view taken substantially along the plane of line 4—4 of Figure 3.

Referring more particularly to the drawings, wherein like numerals designate like parts throughout, the numeral 10 designates generally the cabinet for the record rack and the numeral 12 designates generally the record rack while the numeral 14 designates generally the adjustment means for use in connection with the record rack.

The cabinet 10 may be of any desired form having a back wall 16, top wall 18, side walls

20 and 22, all of the walls being joined together to form a substantially rectangular cabinet with the lower edges of the back and side walls forming supporting surfaces. It should be readily understood that the cabinet may be formed with portions for receiving radio phonograph combinations or the like.

The record rack 12 which is adapted for positioning within the cabinet 10 will now be described. An intermediate wall 24 is secured within the cabinet 10 and in spaced relation to the back wall 16, spacer bars 26 being positioned between the back and intermediate walls for maintaining the spaced relation. A plurality of transversely extending shelf bars 28 are positioned adjacent the open face of the cabinet 10 and connect the side walls 20 and 22 at spaced intervals from top to bottom. Rods 30 are secured to the side walls 20 and 22 and have their ends connected to the shelf bars 28 and the intermediate wall 24 for rigidifying purposes. Transversely disposed along the front face and at the base of the cabinet 10 is the base member 32, members 34 being secured to the side walls 20 and 22 of the cabinet with the ends thereof secured to the back wall 16 and the member 32. An intermediate bar 36 is disposed in parallel relation to the member 32 and is positioned below the intermediate wall 24 for supporting the same. The ends of the intermediate member 36 are secured to the member 34 for support thereby.

A plurality of shelves 38, 40 and 42 are mounted on the members 28 and 30 and 32 and 34. Each of the shelves and the intermediate wall are provided with a plurality of aligned slots 44 and 46, respectively. The width of the slots is preferably formed to receive the ten and twelve inch diameter records.

The adjustment means 14 is provided for converting the phonograph record rack for holding long playing records when desired. The shelves are provided with a plurality of apertures 48 which are disposed in spaced relation to the intermediate wall 24. An elongated rod 50 having a flat supporting surface 52 is provided with a plurality of resilient fingers 54 which are formed in pairs for positioning within the apertures 48 in the shelves. Thus, when it is desired to convert a shelf to long playing record holding means, the elongated rod 50 is positioned on the shelf with the resilient fingers 54 in the apertures 48 for retention thereby.

Suitable indicia means 56 may be marked on the upper surfaces of the bars 28 at 56 whereby

each of the slots 44 may hold a record, the name of which may be determined by looking on an index table. Thus, the records may be inserted into their respective slots by positioning on their respective indicia means and rolling inwardly into their slots.

From the foregoing description, taken in conjunction with the drawings, it is believed that a structure has been provided which will accomplish all of the objects hereinabove set forth. 10

Having described the invention, what is claimed as new is:

A phonograph record rack wherein records of large, small and intermediate diameters may be systematically racked comprising a cabinet having a horizontal member constituting a shelf, a vertical member at right angles to one longitudinal edge of said horizontal member and constituting a back for said shelf, said vertical member having at least one vertical slot therein which is 15 of a prescribed length to accommodate a phonograph record of maximum diameter, said horizontal member having at least one slot opening through one longitudinal edge of the member and communicating with the slot in said vertical member, the opposite end of the slot in said horizontal member being spaced inwardly from the adjacent longitudinal edge of said member 20

5 and said slot being of approximately the same length as the first named slot, an attachable and detachable rod member applicable to said horizontal member and adapted to extend at right angles to a coacting end portion of the slot in said horizontal member, and means for adjustably and detachably connecting said rod member to said horizontal member, whereby the effective record accommodating length of the slot in said horizontal member may be varied according to the diameter of the particular record located in the slot at the time.

DONALD D. PAULDINE.
